CLAIM

The ornamental design for laptop cooling blocks, as shown and described.

DESCRIPTION

FIG. 1 is a front perspective view of a laptop cooling block, showing my new design;

FIG. 2 is a front elevation view of the present embodiment;

FIG. 3 is a rear elevation view of the present embodiment;

FIG. 4 is left side elevation view of the present embodiment, with the right side elevation view being a mirror image thereof;

FIG. 5 is a top plan view of the present embodiment; and, FIG. 6 is a bottom plan view of the present embodiment.
